Attorney.*

UNITED STATES PATENT OFFICE.

WILLIAM R. LYLE, OF RIPON, WISCONSIN.

SCREEN-DOOR.

SPECIFICATION forming part of Letters Patent No. 443,448, dated December 23, 1890.

Application filed May 7, 1890. Serial No. 350,942. (No model.)

To all whom it may concern:

Be it known that I, WILLIAM R. LYLE, a citizen of the United States, and a resident of Ripon, in the county of Fond du Lac and State of Wisconsin, have invented certain new and useful Improvements in Screen-Doors; and I do hereby declare that the following is a full, clear, and exact description of the invention, which will enable others skilled in the art to 10 which it appertains to make and use the same.

My invention relates to certain improvements upon the invention for which Letters Patent were granted to me July 12, 1887, No. 366,489.

15 The invention therein contained consisted, essentially, in a screen-door frame adapted to receive storm-panels upon one side, in combination with strips of grooved molding secured upon the other side of said frame corresponding with the rails and mullions thereof, and storm-door panels secured within said grooves, the object being to permit the panels to be readily inserted and the door converted from a screen to a storm door.

20 25 The above construction, while very effective for the purpose for which it is designed, is objectionable in some respects, principally upon the grounds of the cost or expense, and the object of the present invention is to simplify the construction and provide a screen-door which can be readily converted into a storm-door, and which may be furnished at but a comparatively small expense over the ordinary screen-doors in common use.

30 35 The invention consists in the combination, with a screen-door frame adapted to receive storm-panels upon one side, of strips of molding corresponding with the rails and mullions of the frame and interlocking with each other 40 and with the inner sides of the frame, as hereinafter more fully described.

In the accompanying drawings, Figure 1 is an elevation of the inside of a screen-door which is provided with my improvements.

45 Fig. 2 is a longitudinal vertical section taken on the line $\alpha\alpha$, Fig. 1.

In the said drawings, the reference numeral 1 indicates the frame of a screen-door, and 2 indicates the wire covering-screen which covers the spaces into which said frame is di-

vided, as shown by its middle rail 3 and mullions 4. Both sides of the middle rail and the mullions may be formed or provided with grooves on their under edges, as also the inner sides of the side rails of the frame, to 55 permit of the storm-panels being placed upon that side of the frame, as fully set forth in Letters Patent granted to me April 6, 1886, No. 339,567. Secured upon the other side of the screen-frame are the strips of molding 5, 60 which are preferably provided with grooves 6 to receive the outer edges of the panels. They may, however, be made without grooves or plain, if desired.

The numerals 7 and 8 designate the removable interlocking retaining-strips by means of which the panels are retained in place.

7 designates the cross-strip, and 8 8 the vertical strips, corresponding to the cross-rails and mullions of the screen-frame. These 70 strips may be grooved to receive the edges of the panels, or they may be made plain or without grooves, as desired, they performing their function equally well in either case. At the center of the cross-rail upon each side is 75 a projection or lug 9, which fits over the inner end of each vertical strip 8, which is recessed or cut away at 10 for such purpose, whereby said strips 8 are secured in place. The outer ends of the cross and vertical strips 80 are held in place by means of turn-buttons or wires 11, secured to the screen-frame and capable of being turned in and out of contact with said strips so as to hold or release them. 85

It is obvious that instead of the lug 9 I may recess the under side of the cross-strip and cut away the end of the vertical strips so as to enter and be held in said recesses.

From the above description the manner of 90 applying my invention will be readily understood. When it is desired to convert the screen-door into a storm-door, the cross-strip 7 and the vertical strips 8 8 are removed, and the panels 12, which are preferably composed 95 of some thin pliable material, so that the ends may be sprung into the grooves, as fully set forth in Letters Patent granted to me July 12, 1887, No. 366,489, are placed upon the wire-screen with their outer edges resting 100

in the grooves 6 of the molding 5. The cross-strip 7 is then inserted in position. The vertical strips are then introduced. As before stated, the cross and vertical strips may be 5 grooved to receive the edges of the panels, or they may be made plain, as may be found most convenient or desirable.

The advantages of the invention will be 10 readily understood. It will be seen that the storm-panels can be inserted and secured in position in a few moments, and will thus transform the screen-door into a storm-door, effectually preventing the entrance of rain, wind, or snow, and at the same time will protect the screen from injury or damage.

Having thus described my invention, what I claim, and desire to secure by Letters Patent of the United States, is—

1. The combination, with a screen-door frame provided with detachable cross-strips

and vertical strips and adapted to receive storm-panels upon one side, of the rails and mullions upon the opposite side corresponding with the strips, said strips interlocking with each other and with the door-frame, substantially as and for the purpose set forth. 25

2. The combination, with a screen-door frame and panels, of the cross-strip 7, having lugs 9, the vertical strips 8 8, and fastening device 11 for removably securing said strip 30 to the screen-frames, substantially as described.

In testimony that I claim the foregoing as my own I have hereunto affixed my signature in presence of two witnesses.

WILLIAM R. LYLE.
